UNITED STATES PATENT OFFICE.

EDWIN HAVILAND, OF PLAINFIELD, NEW JERSEY.

DESIGN FOR A TEA-SET.

SPECIFICATION forming part of Design No. 16,073, dated May 5, 1885.

Application filed January 16, 1885. Term of patent 7 years.

To all whom it may concern:

Be it known that I, EDWIN HAVILAND, a citizen of the United States, residing at Plainfield, in the county of Union and State of New Jersey, have invented or produced a new and original Design for a Tea-Set, of which the following is a specification.

My design relates to the several vessels composing a tea-set—such as the tea-pot, cream-pitcher, and sugar-bowl—being also applicable to other analogous vessels.

Figure 1 of the accompanying drawings is a side elevation of a tea-pot embodying all the several features of my design. Fig. 2 is a plan thereof, the cover being omitted. Fig. 3 is a front elevation thereof, and Fig. 4 is a rear elevation thereof. Fig. 5 is a side elevation of a sugar-bowl embodying the principal features of my design, and Fig. 6 is a similar view of a cream-pitcher.

In each of the three embodiments of my design shown the body A of the dish or vessel is of substantially the same form. Seen in plan, as shown in Fig. 2, it has an approximately-square outline, with slightly beveled or convex sides *a a*, (which, however, may be flat instead,) rounded corners *b b*, and slight indentations *c c* at the junction of the sides and corners. Seen in elevation, as shown in Figs. 1, 3, and 4, the lines of the body extend vertically, and are contracted at top and bottom, forming the base B and neck C. The lines of the grooves or indentations *c c* at the junction between the rounded corners *b b* and the sides *a a* extend straight until the points are reached where the contractions begin, and at these points they curve inwardly in convex curves *d d*. The sides *a a* and corners *b b* also curve inwardly with corresponding curves, *d d*. At the termination of the curves *d d*, short vertical lines *e e* connect with them and carry out the designs of the base and neck, respectively. The neck C, viewed in plan, has the same outline as the body A, as seen in Fig. 3, and the base B has in plan the same outline as the neck. These details, however, while contributing somewhat to the general effect, are not strictly essential to my design.

The dish-body or vessel made according to this design has an upright and somewhat rectangular appearance, being, however, devoid of harsh angles or abrupt corners. The sides

a a constitute parallel-sided panels, which at top and bottom curve inward, and are contracted laterally until they join the contracted neck and base. The rounded corners *b b* constitute vertical swelled moldings, which are likewise curved inward at top and bottom to join the neck and base.

The body portion of the dish thus far described is an embodiment of the generic feature of my design, which is equally applicable to either of the three articles shown in the drawings or to other dishes or vessels.

The handle D is curved, and joins the body on one of its flat or square sides, in contradistinction to joining at its corner. The handle at its upper part springs from the flat side *a* at or just beneath its curve *d*. From this point it extends upward, curving outwardly to the top, thence curving downward, and by a long gentle curve reaching finally the lower portion of the side *a* just above its lower curve, *d*. The particular ornamentation on the handle or at the base of the handle is immaterial to my present design, it being only essential that a curved or loop-shaped handle be used planted against the square or flat side of the body portion of the vessel.

The tea-pot shown in Figs. 1 to 4 and the cream-pitcher shown in Fig. 6 have each one handle D, while the sugar-bowl shown in Fig. 5 has two like handles D D.

The tea-pot has a spout, E, which embodies certain specific features of my present design. This spout is square in cross-section, flat upon its lateral sides *f f*, and curved upon its upper and lower (or rear and front) sides, *g* and *h*. At its base, where it joins the body of the vessel, it is somewhat larger than at its nozzle, and is higher than its width, being an elongated rectangle in cross-section. From its base it gradually tapers to its nozzle, the taper of its curved sides *g h* being more rapid than that of its flat sides *f f*. Its front side, *h*, is formed with a convex curve or swell, *m*, as it leaves the base, which turns to a concave, *n*, as it approaches the nozzle. The rear side, *g*, has a slight convex curve corresponding to the curve *n*. The flat sides *f f* have each the pattern or ornamentation in relief shown in Fig. 1, consisting of a stem with a leaf and a series of buds branching therefrom. At the base of the spout is a molding, *p*, having the

(over)

resemblance of a cord passed around in the angle where the spout joins the body, and its end extending onto the sides *ff* of the spout, and there terminating in curves.

5. The tea-pot and sugar-bowl have each a cover, *F*; but the design of this cover forms no novel portion of my present design.

I claim -

10. The design for the vessels constituting a tea-set herein shown and described, the same consisting of the body portion *A*, square in plan, with rounded corners, upright in elevation, with an outline of vertical lines drawn in by convex curves at top and bottom, and 15 meeting a short contracted neck, *C*, at the top and a short contracted base, *B*, at the bottom, said neck and base having vertical surfaces and being approximately square in plan, with rounded corners.
20. 2. The design for the vessels constituting a tea set herein shown and described, the same consisting of the body portion *A*, square in plan, with rounded corners, and with indentations *c c* where the corners join the sides, 25 upright in elevation, contracted at top and bottom by convex curves, and joining a short contracted neck, *c*, and base *B*, and with the lines of the indentations *c c* traversing the body, and extending to and traversing vertically the neck and base.

30. 3. The design for the vessels constituting a tea-set herein shown and described, the same consisting of the body portion *A*, square in plan, with rounded corners, upright in elevation, contracted at top and bottom to join the

neck and base, which are also square in plan, with rounded corners, and a curved handle, *D*, of loop shape, joined to one of the flat sides of the body midway of the corners thereof.

4. The design for a tea-pot herein shown 40 and described, the same consisting of the upright body portion *A*, contracted at neck and base, as shown, square in plan, with rounded corners, and having a curved loop-like handle, *D*, on its rear side, and a square curved spout, 45 *E*, on its front side.

5. In a design for a tea-pot, the upright body portion *A*, square in cross-section, with rounded corners, contracted at neck and base, as shown, with the spout *E*, curved when 50 viewed from the side, and square in cross section, as shown and described.

6. In a design for a tea-pot, the configuration of the spout *E*, with flat sides *ff*, and the ornamentation thereon shown, consisting of a 55 stem extending up the side of the spout, with leaf and buds branching therefrom, as shown and described.

7. In a design for a tea-pot, the body portion *A* and spout *B*, with a rope-like bead, *p*, 60 extending around the base of the spout, and its ends extending onto the sides of the spout, as shown and described.

In witness whereof I have hereunto signed my name in the presence of two subscribing 65 witnesses.

EDWIN HAVILAND.
